UNITED STATES PATENT OFFICE.

MICHAEL J. O'BRIEN, OF NEW YORK, N. Y.

COMBINATION SAFETY DEVICE FOR AUTOMOBILES.

Application filed January 19, 1925. Serial No. 3,473.

To all whom it may concern:

Be it known that I, MICHAEL J. O'BRIEN, citizen of the United States, residing at New York, in the county of New York and State 5 of New York, have invented certain new and useful Improvements in Combination Safety Devices for Automobiles, of which the following is a specification.

This invention relates to an anti-theft lock 10 for automobiles designed to prevent theft of the automobile to which it is applied, or use by unauthorized persons.

The invention has for an object to provide a simple form of combination controlled 15 lock that locks, in open position, a compound switch controlling the spark plug circuits of the engine, and which also serves to lock the emergency brake lever in position with the emergency brake set.

20 For further comprehension of the invention, and of the objects and advantages thereof, reference will be had to the following description and accompanying drawing, and to the appended claims in which the 25 various novel features of the invention are more particularly set forth.

Fig. 1 of the drawing is a plan view showing the device as in position on an automobile, the cover of the box or housing being 30 thrown back.

Fig. 2 is a side view of the device as applied.

Fig. 3 is a longitudinal sectional view of 35 the device, this view being taken on the line 3—3 of Fig. 4.

Fig. 4 is a horizontal sectional view taken on the line 4—4 of Fig. 3 and looking upward.

40 Fig. 5 is a detail plan view showing more particularly the compound spark plug control switch.

Fig. 6 is a transverse sectional view taken on the line 6—6 of Fig. 5.

45 Fig. 7 is a fragmentary horizontal section taken on the line 7—7 of Fig. 3.

My improved device comprises a box 10 that is fixed to the automobile floor in front of the driver's seat, a portion of the said floor being indicated at 11. Extending 50 across this box 10, approximately midway of its height, is a horizontal partition 12 below which are the lock and switch mechanisms, while the knob 14 for the combination lock, and the handle 15 for throwing 55 the locking bolt are supported by and above this partition, the numbered dial, with which

the knob 14 co-operates, being shown at 16 on the partition.

The handle 15 is fixed on the upper end 60 of a spindle 20 extending through, and rotatable in, the partition 12, this spindle having fixed to its lower end an angular lever arm 21, one arm 21' of which is engaged in a notch 22 in a switch operating plate 23, while the other arm 21^a is engaged by the 65 bolt 24 of the lock, this arm having an angular recess 25 in the end thereof that engages the end of the bolt, the swing of the arm being transverse to the direction of 70 movement of the bolt, the latter being slideable in a casing 26 containing ordinary lock mechanism controlled by the knob 14.

The switch operating plate 23 is slideable 75 in the box 10, under the partition 12, and is guided partly by a headed screw 30 passing through a slot 31 in the plate and screwed into the partition 12 and partly by means of a projecting pin 32 fixed to said plate 23 and engaged in an aperture in a transverse 80 rib 34 depending from the partition 12, and to which further reference will presently be made.

The switch operating plate 23 is provided at one end with a transverse cross-piece 23' which has attached thereto one end 85 of a rod 38 that extends parallel to the direction of movement of the plate. To the other end of this rod is attached a compound bridging element alined with said rod that bridges contact members forming part of the individual circuit to the various spark 90 plugs of the automobile engine. These contact members comprise the studs 40 that are sunk in a pair of elongated insulating base-blocks 41 between which the said bridging 95 element extends, these studs having their adjacent ends rounded as shown and projecting slightly beyond the vertical surfaces of the blocks. Connected to these studs, as shown are the vertical binding screws 44 to which the leads to and from the spark plugs 100 connect. The contact supports 41 may be mounted on a bracket fixed to the bottom of the box and having upturned ends 46' which are apertured, the one to receive the end of the rod and the other to receive an extension 46 105 from the other end of the contact bridging element whereby the latter is guided for movement between the rows of contacts. This bridging member is in the form of a bar 48 having a series of studs fixed therein 110 that are spaced therealong in correspondence to the spacing of the contact studs.

The member 48 is normally urged to a position with the studs thereon to engage the respective pairs of studs by means of a coiled expansion spring 50 surrounding the rod 38 and bearing on a collar 51 fixed thereon, the movement of the said member under the influence of the said spring being limited by a nut and washer element indicated generally at 52 that bears on the end of the bracket 46.

Referring now to the rib 34 before mentioned as depending from the partition 12 and apertured to receive the pin 32 on the plate 23, the said rib is formed with a socket 55 that is entered longitudinally thereinto from the side of the casing and in which is slidably positioned a flat bar 56 that has a hole 57 therein, near its inner end, through which the pin 32 projects to lock the said bar in place, while the outer end of the bar 56 projects beyond the side of the casing, parallel with the bottom thereof, and is formed with another aperture or hole that receives a stud 57^a on the side of a collar 58 that freely surrounds the emergency brake lever 59 thereby locking the said lever in place. The box may be provided with a sliding cover made in sections 60 that overlap one another when the cover is opened, and may have an electric lamp 61 in the top compartment thereof to enable the dial of the combination lock to be seen at night.

In connection with my improved attachment I preferably provide a device that ensures the release of the emergency brake lever before the bridging element 48 is moved sufficiently to close the ignition circuits. As shown in Fig. 7 the pin 32 is formed with a notch 65 in which is adapted to be engaged a spring pawl 66 secured on one end of an angular rock lever 67 whose other end projects through a slot 68 in the rib to bear on the bar 56, a weak tension spring 69 being connected to this lever and urging it in a direction to move the pawl 66 away from the pin 32. When the bolt is released the pin 32 may be moved with the plate 23, sufficiently to disengage from the bar 56 before the pawl 66 rides into the notch 65, at which point the contacts of the ignition control device are not as yet bridged. The bar 56 must then be withdrawn, to allow the lever 67 to swing under

the influence of the spring 69 to free the pawl 66 from the notch 65. The lever is provided with a cam element 67' that is engaged by the end of the bar 56 when the latter is inserted in place to locking position.

Having thus described my invention, what I claim as new and desire to protect by Letters Patent of the United States is as follows:

1. An anti-theft attachment for automobiles comprising a series of spaced contacts arranged in pairs forming part of the ignition circuit of the automobile, a slidable bridging element adapted to engage and bridge the contacts of the respective pairs, a collar adapted to freely surround the emergency brake lever of the automobile, a bar connected at one end to the said collar, a pin movable with the said bridging element and engaging in an aperture in the said bar to retain the same against movement, and a lock controlling the movement of the said pin and bridging element, and means preventing complete movement of the said bridging element to operative position when the said pin is engaged with the said bar.

2. An anti-theft attachment for automobiles comprising a series of spaced contacts arranged in pairs forming part of the ignition circuit of the automobile, a slidable bridging element adapted to engage and bridge the contacts of the respective pairs, a collar adapted to freely surround the emergency brake lever of the automobile, a bar connected at one end to the said collar, a pin movable with the said bridging element and engaging in an aperture in the said bar to retain the same against movement, and a lock controlling the movement of the said pin and bridging element, and means preventing complete movement of the said bridging element to operative position, when the said pin is engaged with the said bar, comprising a lever, a pawl carried by said lever and adapted to engage in a notch in the said pin, said lever having a part projecting into the path of the said bar whereby the lever is retained by the said bar in position with the said pawl bearing on the said pin.

In testimony whereof I have affixed my signature.

MICHAEL J. O'BRIEN.
